[57] CLAIM

The ornamental design for a combined shaver head guard and brush therefor, as shown and described.

DESCRIPTION

FIG. 1 is a top plan view of a combined shaver, head guard and brush therefor showing my new design;

FIG. 2 is a left side elevational view;

FIG. 3 is a front elevational view, it being understood that the raised surface configuration is continuous over the area indicated by dot-dash lines;

FIG. 4 is a right side elevational view;

FIG. 5 is a rear elevational view; and

FIG. 6 is a bottom plan view.
